CONTROL MEANS FOR HIGHWAY
CROSSING SIGNALSNeil D. Preston, Rochester, N. Y., assignor to
General Railway Signal Company, Rochester,
N. Y.

Application December 19, 1930, Serial No. 503,555

4 Claims. (Cl. 246—130)

This invention relates to signalling systems particularly adapted for protecting vehicle traffic on highway crossings over railroads, and more particularly to the control of a highway crossing signal of any suitable type.

In accordance with this invention, it is proposed to provide means, governed by trains approaching a highway crossing, which will act to actuate the highway crossing signal at a substantially fixed and uniform time interval before the arrival of the train at the crossing, irrespective of the speed of the approaching train.

Other characteristic features, objects, and advantages of the invention will be in part apparent, and in part pointed out, as the description progresses.

In the accompanying drawings, Fig. 1 illustrates in a simplified and diagrammatic manner one embodiment of the invention, the various parts being shown more with the object of making it easy to understand the nature of the invention, than to show the detail construction and arrangement of parts preferably employed in practice;

Fig. 2 shows how the invention may be applied to a single track railroad, or other stretches of track, where trains approach the highway crossing from both directions; and Fig. 3 shows a modified embodiment of the invention, in which provision is made for discontinuing the warning indication of a highway crossing signal after it has been given longer than a predetermined time. Fig. 4 shows a modified form of the invention, in a wholly diagrammatic manner.

Referring to Fig. 1, H designates a highway crossing a railroad at grade, and G designates an electrically controllable highway crossing signal of any suitable type, which may be any one of the well-known types of bells, wigwag signals, flashing light signals, and even power-operated gates. The railroad track on one side of the crossing, dependent upon the normal direction of train movements, is provided with two insulated track circuit sections T—1 and T—2, having track relays 1T and 2T. The track circuit section T—2 extends from the crossing to a predetermined point B distant from the crossing; and the track section T—1 extends from the point B to a point A farther away from the crossing. The length of the track circuit section T—2 and the proportional length of the other track circuit section T—1 are selected in accordance with the principles hereinafter explained.

The highway crossing signal G (indicated conventionally as a bell) is controlled by the track relays 1T and 2T, and also by a timing mechanism, which in the simplified arrangement shown comprises a cam 5, co-operating with a roller 6 5 to open and close pairs of spring contacts 7 and 8.

The contacts 7 and 8 are biased to the open position by their own spring pressure, or if desired an extra spring may be provided to urge 10 the roller 6 toward the cam 5. The cam 5 is fixed to a shaft 9, indicated by dotted lines, and a pinion 10 on this shaft operates a pivoted weighted sector 11, having its lower position fixed by an adjustable stop screw 12. Also fixed to 15 the shaft 9 is a gear 13, having a mutilated portion 14, which forms part of a reduction gearing of any suitable type, including gears 15, 16, and 17. The gear 17 is fixed to a shaft 18, which is connected to the armature of an electric motor 20 M of any suitable type having constant speed characteristics. Also fixed to the shaft 18 is a ratchet wheel 19 engaging a spring pawl 20 carried by a gear 21 loose on the shaft 18. This gear 21 drives a pinion 22 which is connected to 25 a shaft 23 supporting and operating a centrifugal brake and circuit controlling device CB. As diagrammatically shown, this centrifugal device CB is of the usual fly-ball governor type, which raises an insulated contact disc 24 out of engagement with stationary contacts (indicated as arrows), and into engagement with stationary brake members 25.

The arrangement shown in Fig. 1 also preferably includes special control of a wayside automatic block signal governing train movement toward the crossing. This signal S, shown conventionally as a semaphore signal, is located at the entrance end of the track section T—1, and is assumed to be controlled by a line relay HD, 40 in accordance with recognized practice. The energizing circuit of this line relay HD includes a front contact 30 of the track relay 1T, contacts 7 of the timing mechanism, and various other controlling contacts (designated conventionally at 31) which are necessary to provide the desired control of the signal S.

Other features of construction and characteristic features of this invention will be made clear upon considering the mode of operation.

When the head-end of a train approaching the crossing passes the point A and enters the track section T—1, the track relay 1T is shunted, and the motor M is energized over a circuit which may be traced from (+) (designating one ter- 55

5 minal of a suitable source of operating current), through front contact 32 of the track relay 2T, wire 33, back contact 34 of track relay 1T, wires 35 and 36, and motor M to (—) (indicating the opposite terminal of said source of current). At 10 the same time, the slow-release relay SL is energized in multiple with the motor. The motor M, being thus supplied with current, drives the shaft 18 at a uniform rate in a counter-clockwise direction, causing the pawl 20 to click idly over the ratchet wheel 19. Also the shaft 18 through the reduction gearing drives the shaft 9 in a counter-clockwise direction, indicated by the arrow a, raising the weighted sector 11.

15 This operation, conveniently considered as a winding-up operation, continues until the head end of the approaching train passes the point B and enters the track section T-2, whereupon the track relay 2T is shunted, the energizing circuit for the motor M is broken at its front contact 32, and the motor M is de-energized. The motor M being de-energized, the weighted sector 11 drives the shaft 9 in the opposite or clockwise direction, indicated by the arrow b.

20 Likewise the shaft 18 is driven in the same direction, rotating the gears 21 and 22, and the centrifugal brake CB, through the ratchet wheel 19 and pawl 20. This centrifugal brake CB retards this run-down movement of the shaft 9 and cam 5 to a predetermined rate, and after a 25 time the cam 5 closes the contact 8, and the highway crossing signal G is energized over a circuit from (+), through the back contact 32 of the track relay 2T, wire 37, contacts 8, wires 38 and 39, signal G, to (—).

30 The operation of the system embodying this invention, thus briefly described, involves a number of factors of speed, time, and distance, which determine the lengths of the track sections T-1 and T-2, and the design and proportion of parts of the timing mechanism, so 35 as to obtain the result desired. Analyzing the principles governing the operation of the invention, it will be noted that the energizing circuit for the signal G, which is closed to cause this signal to give its warning of an approaching train, includes in series the back contact 32 of the track relay 2T and the contacts 8 of the timing mechanism. This back contact 32 is 40 closed when the approaching train passes the point B and shunts the track relay 2T; but the signal is not actuated until the contacts 8 of the timing mechanism are also closed. These contacts 8 of the timing mechanism are opened 45 during the wind-up operation (rotation of shaft 9 in direction indicated by arrow a), which takes place while the approaching train is passing over the distance between the points A and B.

50 It should be noted the contacts 8 are closed by the cam 5 in its initial run-down position, and remain closed during the angular movement of the cam designated x. Consequently, during the wind-up operation of the timing mechanism the contacts 8 remain closed, until the cam 5 has 55 been rotated counter-clockwise through the angular distance x, far enough for the roller 6 to ride off of the end of the cam surface; whereas, during the run-down operation of the timing mechanism (rotation of shaft 9 in direction indicated by arrow b), the contacts 8 are closed as soon as the cam reaches an intermediate point, corresponding to the angular distance x from its initial run-down position. In short, the 60 time interval represented by the angular dis-

65 tance x, for a given rate of rotation of the shaft 9, is a part of the wind-up time, but is subtracted from the run-down time. This interval of time, corresponding to the angular distance x of rotation of the cam 5 at a given rate, represents the time considered necessary and safe for vehicles approaching or passing the railroad to come to a stop or clear the crossing, after the signal G has been actuated, and before the approaching train actually reaches the crossing. 10 This time interval, which may be considered to be the safe clearing time for the railroad crossing, may be varied by adjusting the initial rundown position of the cam 5 by means of the screw 12. It will be evident that adjustment of 15 the screw 12 up or down will lengthen or shorten the angular distance x.

15 The track section T-2 is made at least as long as, and preferably longer than, the distance over which a train running at maximum speed will travel during the clearing time selected as safe for actuating the signal G before this high speed train actually reaches the crossing. In other words, the length of the track section T-2 is such, that if the signal G is actuated to give the warning of an approaching train, running at maximum speed, enters the track section T-2, a safe clearing time for vehicles to stop or clear the crossing will elapse before this high speed train actually arrives at 30 the crossing.

Having thus determined the length of the track section T-2, the adjacent track section T-1 is made of such length as to have the same ratio to the length of the track section T-2 as 35 the ratio of the rate of wind-up movement of the cam 5 to the rate of its run-down movement. For example, if the centrifugal brake device CB is designed and adjusted to regulate the rate of the return movement of the shaft 9 in the 40 clockwise direction (indicated by arrow b) to the same rate at which this shaft is rotated in the counter-clockwise direction by the motor M, then the track sections T-1 and T-2 are made substantially the same length. If, however, the 45 rate of the run-down movement is made slower than that of the wind-up, as can be readily accomplished by proper proportioning of the parts, then the track section T-1 is made proportionally shorter than the track section T-2. Stated 50 another way, with given rates of rotation of the shaft 9 and cam 5 for wind-up and run-down movements, determined by the design and proportioning of the parts of the timing mechanism, the relative lengths of the track section 55 T-1 and T-2 are selected in the installation of the invention, so as to cause the cam 5 to rotate through the same angular distance during the movement of a train travelling at uniform speed through these track sections.

60 Bearing in mind these factors of time and distance which determine the proportioning of the parts for an installation of this invention, it will be observed that the timing mechanism is wound up during the time taken by the approaching train to travel the distance between the points A and B, corresponding to the length of the track section T-1, the operation of the timing mechanism being initiated by the shunting of the track relay 1T to close its back contact 34, and being terminated by the shunting of the track relay 2T to open its front contact 32. Thus, the angular movement of the cam 5 from its initial run-down position taking place 70 during the wind-up operation of the timing 75

mechanism varies with the speed of the approaching train. The higher the speed of this train, the shorter the time interval of the winding operation, and the smaller the angular movement of the cam 5.

When the approaching train passes the point B, the run-down operation of the timing mechanism starts, and after a time interval which depends upon how far cam 5 was rotated during the wind-up operation, the contacts 8 are closed to actuate the signal G. With a train running at the maximum speed, the cam 5 is moved during the wind-up operation to a point only a short distance beyond the point where the contacts 8 are closed, so that these contacts 8 are quickly closed after the train enters the track section T-2 and the run-down operation starts. In other words, for a train running at maximum speed, the signal G is actuated at about the time this train passes the point B. If the length of the track section T-2, from the point B to the crossing, is such that this maximum speed train will reach the crossing at the selected clearing time, represented by the angular distance x, then the contacts 8 close promptly upon shunting of the track relay 2T; but with a longer track section T-2, the cam 5 may be moved during the wind-up operation farther than the angular distance x and the closing of the contacts 8 is delayed for a corresponding time interval.

In the case of a slow-speed train approaching the crossing, the cam 5 is rotated counter-clockwise much further than the angular distance x, dependent upon the speed of the train and the time taken by it to travel through the track section T-1; and it will be evident that there is a corresponding delay in the closing of the contacts 8 after this train enters the track section T-2, so that the actuation of the signal G is delayed until such slow-speed train has reached a point where the time required for this train at the same speed to reach the crossing is the selected safe clearing time, represented by the angular distance x.

In this way this invention provides means which causes actuation of a highway crossing signal to give warning of an approaching train at substantially a fixed and uniform time before such train actually reaches the crossing, regardless of the speed of this approaching train. Without the special control of a highway crossing signal in accordance with this invention, it will be evident that the signal must be given at a fixed point, located a predetermined distance from the crossing and far enough away to actuate the signal in time for the highest speed approaching train, with the result that the signal is given long before a slow train actually reaches the crossing. With such a control of a highway crossing signal on the fixed distance interval basis, the operators of vehicles obeying the signal frequently have to wait at the crossing for a slow train so long that they lose confidence in the signal; and after some unnecessary long waits at crossings, when strictly obeying the indication of the signal, the operators of vehicles frequently disregard the signal, thinking that there is plenty of time to cross the railroad before the train arrives, this being done sometimes even though the approaching train can be seen. It is very difficult, however, to judge the speed of an approaching train, particularly at night; and accidents have occurred where the operator of the vehicle, having become accustomed to disregard the indications of the highway crossing

signal and to rely on his own judgment of the time of arrival of the approaching train, makes an error in judgment and does not have time to cross the track ahead of a fast train. This invention obviates these dangerous conditions and obtains the proper and desired control of a highway crossing signal by indicating, not only that there is a train approaching, but also that there is a definite limited time available to clear the crossing before the train will actually reach the crossing, so that the operator may govern his vehicle accordingly with safety and without unnecessary delay.

The clearing time, between the actuation of the signal G and the actual arrival of the train, will of course be exactly the same for different speed trains, within the limits of accuracy of the timing mechanism, only if each train maintains a uniform speed between the point A and the crossing. If the approaching train materially changes its speed in this distance, this clearing time will be somewhat shorter or longer. A railroad train, however, cannot quickly change its speed, and a clearing time can readily be selected to provide the desired safety, without producing unnecessary delay, in spite of such variations of train speed encountered in practice. On account of such speed variations, it is preferred to make the track section T-1 relatively short, so that the wind-up movement of the cam 5 is a substantially accurate measure of the actual running speed of the train. For example, if the track section T-1 were made as short as 200 feet, it is evident a railroad train could not materially alter its speed in travelling such a short distance, either in accelerating or in braking. If a train should slow down after passing the point B, then the signal G is actuated sooner than necessary to provide the selected clearing time; and if the train should accelerate after passing the point B, the clearing time is shortened. These variations can be taken care of for all practical purposes by selecting the proper clearing time interval.

In order that the timing mechanism may not be damaged in case a train should happen for any reason to stop in the approach timing track section T-1, the gear 13 is provided with a mutilated portion 14, so positioned that when this gear 13 and the shaft 9 have been rotated to the extreme woundup position, the gear 15 turns idly in this mutilated portion. If desired, a suitable friction clutch may be interposed between the motor and the shaft 18 for the same purpose.

In such a system of signalling for highway crossings, it is important that all probable failures of the mechanism and circuits should, as far as practicable, be on the side of safety. In the embodiment of the invention shown, if the timing mechanism should for any reason fail to wind up, the contacts 8 remain closed, and the signal G is actuated as soon as the approaching train enters the track section T-2. If the timing mechanism, having been wound up to a position to open the contacts 8, should for any reason stick in that position and fail to return and close these contacts, the signal G would not be properly actuated; and to protect against this contingency, an auxiliary circuit for displaying the signal G is provided from (+), back contact 32 of track 2T, wires 37 and 40, back contact 41 of relay SL, wire 42, contacts 24 of the centrifugal brake device CB, wires 43 and 39, signal G, to (-). If the timing mech-

anism, after having been wound up, should fail to return, the centrifugal device CB is not rotated and its contacts 24 remain closed. Consequently, when the approaching train enters the track section T-2 and breaks the energizing circuit for the relay SL at the front contact 32 of the track relay 2T, the back contact 41 of the relay SL closes, and the signal G is actuated, even though the contacts 8 may be open. The relay SL is made sufficiently slow releasing, by the use of copper slugs or any one of the various well-known expedients, so that upon simultaneous de-energization of this relay and the motor M, there will be sufficient time for the weighted sector 11 to start the rundown movement and open the contacts 24 of the centrifugal brake device CB before the back contact 41 of the relay SL is closed.

As a further check upon the performance of the timing mechanism of this invention, if desired, the wayside block signal S, governing traffic toward the siding, may be controlled by the contact 7 as shown, so that if the contact 8, which is mechanically connected to and operated concurrently with the contact 7, is open for any reason, the block signal S is held at stop, thus manifesting a defect in the operation of the highway crossing system. It is contemplated that the engineers of passing trains, finding the block signal S at stop, when there is no train ahead, will report the matter, so that the failure of the timing mechanism will be quickly discovered and remedied.

In the arrangement shown in Fig. 1, it is assumed that trains always approach the crossing in one direction; and Fig. 2 illustrates how the principles of the invention may be applied to a single track railroad, or other track location, where trains may approach the crossing from either direction.

In making such an application of the invention, any one of the well-known types of interlocking or stick relay circuits now commonly employed for controlling highway crossing signals, may be used to control the timing mechanism of this invention. In the arrangement shown in Fig. 2, two track sections, corresponding to the track sections T-1 and T-2 of Fig. 1, are provided on each side of the highway crossing; and the track relays 1T and 2T, and 3T and 4T, of these track sections control the energization of the two coils RE and RW of an interlocking relay of the usual type, such as disclosed for example in the patent to T. L. Lee, No. 885,061, dated April 21, 1908. When both of the coils RE and RW of such an interlocking relay are energized, then upon de-energization of either coil, the armature of that de-energized coil may drop down and close its back contact, and lock up the armature of the other coil.

Considering the operation of this arrangement shown in Fig. 2, assume that an east-bound train, travelling from left to right, enters the track section T-1. The opening of the front contact 45 of the track relay 1T de-energizes the coil RE of the interlocking relay, closing its back contact 46 and establishing an energizing circuit for the motor M from (+), back contact 46, wire 47, front contact 48 of relay 2T, wires 49 and 50, motor M to (-). When this approaching train enters the track section T-2, the opening of the front contact 48 of the track relay 2T breaks the energizing circuit for the motor M of the timing mechanism; and the

closing of the back contact 48 of this relay 2T establishes a circuit for actuating the signal G from (+), back contact 46 of coil RE of the interlocking relay, wire 47, back contact 48 of track relay 2T, wires 51 and 52, contacts 8 of the timing mechanism, wire 53 and signal G to (-). When this train passes the crossing H and enters the track section T-3, the dropping of the track relay 3T de-energizes the coil RW of the interlocking relay, but since the coil RE was first de-energized, the armature of the coil RW is locked up, and remains so until the train in question has passed out of the track section T-4. When the rear end of the train passes the crossing H and enters the track section T-3, the track relay 2T picks up, breaking at its back contact 48 the circuit for the signal G, and at the same time energizing the coil RE to open its back contact 46.

The operation is the same for a west-bound train travelling in the opposite direction; and it can be readily seen that the signal G is actuated to give warning of a train approaching the crossing from either direction, with the same control by the timing mechanism as previously explained in connection with Fig. 1.

Highway crossings are sometimes located at such places along a railroad that trains occasionally come to a stop and wait for a long time, or switch back and forth, near the crossing within the control limits for the highway crossing signal. For example, a turn-out switch SW may be located, as shown in Fig. 3, in or close to the track section T-2 adjacent the crossing, so that this track section T-2 may be occupied for a long time by a train switching cars over this switch SW. In cases of this kind, the highway crossing signal G may be actuated to display its warning indication and block the crossing for a long time; and it is desirable to provide means for discontinuing this warning indication, notwithstanding the presence of a train adjacent the crossing, when such train is standing still, or will not actually pass the crossing for some time. Accordingly, this invention contemplates the provision of means, such as shown in Fig. 3, for cutting off or suppressing the warning indication of the signal G after a time interval. In this connection, it should be understood that, when a train for any reason, after entering the track section T-2, is delayed for a considerable time before passing over the crossing, its movement over the crossing will be made at a slow speed and with suitable hand signal protection for the vehicles on the highway.

Referring to the modification shown in Fig. 3, a thermal time element device TE and a stick relay S, with suitable control circuits, are provided to shunt or short-circuit the signal G after this signal G has been actuated for a predetermined time by a train on the track section T-2. The thermal time element device TE is of the type shown and described, for example, in the application of J. E. Willing, Ser. No. 463,903, filed June 26, 1930, and comprising a bi-metallic member 55, surrounded by a heating coil 56. When the heating coil 56 is supplied with current, the member 55 is heated and is bent or displaced from its normal cold position, this displacement being gradual and substantially in accordance with the lapse of time. The member 55 engages contacts indicated by arrows in its normal cold position, and in its heated position. In this modified arrangement shown in Fig. 3,

when the signal G is actuated, as previously explained, by the closing of the contacts 8 of the timing mechanism and the back contact 32 of the track relay 2T, another pair of spring contacts 57, mechanically connected to the contacts 8, are also closed, and another back contact 58 of the track relay 2T is likewise closed, thereby establishing a circuit for supplying current to the heating coil 56 of the time element 10 device TE from (+), through the back contact 59 of the stick relay S, wire 60, heating coil 56 connected to the member 55, wire 61, contacts 57, wire 62, back contact 58 of track relay 2T to (-). After a predetermined time, dependent 15 upon the design and proportioning of the parts of the thermal element and the intensity of its heating current, the member 55 is bent or displaced far enough to close its normally open contact, whereupon a pick-up circuit for the 20 stick relay S is established from (+), relay S, wires 63 and 64, member 55 in its heated position, wire 61 contact 57, wire 62, back contact 58 of the track relay 2T to (-). Upon energization 25 of the stick relay S, it is maintained energized by a stick circuit through its own front contact 59 and the contacts 57 and 58, in series with the heating coil 56. The resistance of the relay S is such as to reduce the current through the heating coil 56 to such a small amount that 30 the thermal member 55 gradually cools off; and when this member 55 returns to its normal cooled position, after a further lapse of time, a partial circuit for shunting out the signal G and causing it to assume its inactive condition 35 is established, from wire 39, over wire 66, suitable limiting resistance 66, wire 67, front contact 68 of relay S, wire 69, member 55 in its cooled off position, wire 61, contacts 57, wire 62, and back contact 58 of track relay 2T 40 to (-).

Thus, after a predetermined time interval, necessary for the thermal member 55 to become heated and then again cooled, the highway crossing signal G is cut out or suppressed. When 45 the train on the track section T-2, causing actuation of the signal G, leaves this track section, and the back contact 58 of the track relay 2T is opened, the stick relay S is de-energized, and the parts are restored to the normal condition, ready 50 for the next operation.

In some types of highway crossing signals, particularly the type commonly known as wig-wag signals, the signalling device is actuated to display its warning indication by opening a 55 normal closed and energized circuit, rather than closing a circuit; and Fig. 4 illustrates how the control circuits for a signal of this type can be organized in accordance with this invention.

Referring to Fig. 4, the signal G is assumed 60 to be controlled by a normally energized control relay GR and to be actuated when this relay is de-energized. The control relay GR is normally energized over a circuit from (+), front contact 70 of the track relay 2T, wires 71 and 65 72, relay GR to (-). When the approaching train enters the track section T-2, the opening of this front contact 70 of the track relay 2T breaks this circuit for normally energizing the relay GR, and unless an auxiliary energizing 70 circuit for said relay is established, the signal G is actuated.

In this modified arrangement shown in Fig. 4, the cam 51 is shaped to close normally open contacts 81 after this cam has been displaced 75 from its normal run-down position through the

angular distance x. The timing mechanism is wound up during the movement of the approaching train through the track section T-1, and when this train enters the track section T-2, the opening of the front contact 70 of the track 5 relay 2T de-energizes the motor M and the relay SL, in the same way as previously described. The control relay GR is maintained energized under these conditions by a circuit from (+), contacts 81, wires 73 and 74, front contact 75 of relay SL, wires 76, 77, and 78, relay GR to (-). When the timing mechanism begins its run-down movement, the contacts 24 of the centrifugal device CB close before the front contact 75 of the relay SL opens, and the 15 control relay GR is maintained energized until the cam-operating contact 81 opens. If the timing mechanism should fail to start and close the normally open contacts 81 or should fail to run down and close the contacts 24 of the centrifugal brake device CB, the relay GR is de-energized upon opening of the front contact 70 of the track relay 2T, thereby actuating the signal G, in spite of such failures.

The embodiments of the invention shown and 20 described are merely illustrative or typical of the ways in which the principles of the invention may be practiced; and various additions, modifications, and adaptations may be made in the particular construction and arrangement of 25 parts and circuits shown and described, without departing from the invention. It should be understood that any type of highway crossing signal may be actuated in accordance with this invention; that any desired source of current may 30 be employed for the energization of this signal and its control devices and circuits; and that train actuated track instrument devices may be used instead of the track circuits.

What I claim is:—

1. In a signalling system for highway crossings on railroads, the combination with a signal at the crossing, a timing mechanism wound up from an initial position at a predetermined rate during the time taken by an approaching train to 45 travel a predetermined distance remote from the crossing, said timing mechanism automatically returning to said initial position at a predetermined rate and actuating circuit controlling means at a time interval prior to reaching 50 said initial position, contacts closed only when said timing mechanism is returning to its initial condition, and a circuit governed by said circuit controlling means and said contacts for controlling said signal. 55

2. In combination, a stretch of railway track intersected by a highway, a crossing signal located at the intersection, means for setting the signal into operation when a train approaching the intersection reaches a fixed point, a time 60 measuring device comprising a member biased to an initial position and a prime mover moving it away from such position, means for energizing said prime mover before a train reaches said fixed point and for de-energizing it when the 65 train reaches such fixed point, means including said measuring device for delaying the operation of said signal, and means for cutting said delaying means out of service if said member stops even temporarily during the portion, necessary 70 for signal initiation, of its return movement.

3. In combination, a stretch of railway track intersected by a highway, a crossing signal located at the intersection, means for setting the signal into operation when a train approaching 75

the intersection reaches a fixed point, a time measuring device comprising a member biased to an initial position and a prime mover moving it away from such position, means for energizing said prime mover before a train reaches said fixed point, means including said measuring device for delaying the operation of said signal, and means for at once cutting said delaying means out of service if said member stops during a predetermined portion of its return movement.

4. In combination, a stretch of railway track intersected by a highway, a crossing signal lo-

cated at the intersection, means for setting the signal into operation when a train approaching the intersection reaches a fixed point, a time measuring device comprising a member biased to an initial position and a prime mover moving it away from such position, means for energizing said prime mover before a train reaches said fixed point, means including said measuring device for delaying the operation of said signal, and means for cutting said delaying means out of service if and when said member stops during its return movement.

NEIL D. PRESTON.
